CONDUIT HOLDING CLIP

Fernando V. Guerrero, Chagrin Falls, Ohio, assignor to Continental Oil Company, Ponca City, Okla., a corporation of Delaware

Filed Jan. 24, 1968, Ser. No. 10,286

Term of patent 14 years

(Cl. D54—1)

FIG. 1

FIGURE 1 is an isometric view showing the base, one side, and one end of the clip according to my new design,

The broken lines showing a conduit are for illustrative purposes only.

I claim:

The ornamental design for a conduit holding clip, as shown and described.
